UNITED STATES PATENT OFFICE.

CLIFTON D. PETTIS, OF NEW YORK, N. Y.

CASTING MOLD.

Application filed May 7, 1923. Serial No. 637,165.

To all whom it may concern:

Be it known that I, CLIFTON D. PETTIS, a citizen of the United States, residing in New York city, in the county of New York and State of New York, have invented certain new and useful Improvements in Casting Molds, of which the following is a specification.

This invention relates to molds for the casting of metal but more particularly to that class of casting molds designed to be repeatedly used in the casting operation and commonly designated "permanent molds."

The primary object of the present invention is to produce a mold of the type described which is simple and durable in construction and which may be quickly and easily operated to provide a large output.

Further objects of my invention are to reduce the number of parts of the mold, to facilitate the cooling of the casting, to eliminate the usual cope member of the mold, to facilitate the inclusion of chills in the mold, and in general to provide a new and improved mold construction.

The many other objects and advantages of my invention will be better understood by reference to the following specification when considered in connection with the accompanying drawings illustrating certain selected embodiments thereof, in which:

Fig. 1 is a side elevation of the casting mold complete with the parts in closed position.

Fig. 2 is the same as Fig. 1, plan view.

Fig. 3 is the same as Fig. 1, end elevation.

Fig. 4 is a transverse vertical section on the line 4—4 of Fig. 2.

Fig. 5 is a vertical longitudinal section on the line 5—5 of Fig. 2.

Fig. 6 is the same as Fig. 5, in part, showing the steel shell in position in the mold.

Fig. 7 is the same as Fig. 4, in part, showing the steel shell in position in the mold.

Fig. 8 to 16 are detail views.

Fig. 17 is a plan view of one type of steel shell.

Fig. 18 is a central longitudinal section of the steel shell shown in Fig. 17.

Fig. 19 is a plan view of a modified form of mold.

Fig. 20 is a section on the line 20—20 of Fig. 19.

Fig. 21 is a transverse vertical section on the line 21—21 of Fig. 20.

Fig. 22 is a partial section on the line 22—22 of Fig. 19.

Figs. 23 to 25 inclusive are detail views of a modified form of pouring gate, and

Fig. 26 is a detail view of another modified form of pouring gate.

Referring to the drawings, it will be seen that the particular designs of casting molds which I have selected to illustrate the principles of my invention are intended for the casting of railway brake shoes but it should be clearly understood that these principles are equally applicable to molds for casting many other articles.

Referring particularly to Figs. 1 to 18 inclusive, the mold is mounted upon a suitable base A of cast metal and comprises a plurality of separable sections or members forming a flask or holder, each member carrying a corresponding part of the molding receptacle. To this end the base A is provided with upstanding box-shaped supports 30 which are perforated to receive the corresponding ends of a pivot rod 33. This pivot rod 33 passes through lugs 34 depending from the bottom of movable side members B, B of the mold. A stationary bottom member C is mounted on these supports 30 between the side members B, B.

In the present embodiment of my invention each of the members B and C includes a metal frame or flask section, the outer walls of the members B being preferably perforated, as at 35, to provide ventilation. Chambers, as 36, in these members permit free circulation of air about the molding receptacle, to be presently described.

The walls of the molding receptacle with the exception of a portion of the top comprise a plurality of blocks arranged in groups or sections, each section being carried by the corresponding flask section. At the portions of the receptacle where it is desired to chill the casting, these blocks are preferably of metal. The remaining blocks are preferably formed of some highly refractory material, such as carborundum, that may be readily molded into the desired form. All blocks would preferably be of refractory material when no chilling of the casting is required. The blocks are assembled in the several sections or members composing the holding frame or flask with sufficient spacing between the blocks of a section to permit expansion but insufficient

amount to cause the blocks to fall out of the sections. The sections are held together by a suitable adhesive.

to allow the molten metal to flow into the interstices.

The frame or flask of the base section C in the present embodiment comprises end 5 pieces 40 formed integral with the supports 30 and connected by a plate 41. Refractory blocks D are mounted in this flask section and held in place by a key or guard plate 42 which is attached to the end pieces 40 by 10 screws 43 or other suitable means. The plates 41 and 42 are each provided with a rib, as 44, which fits within a corresponding groove in the blocks D. The end blocks are 15 cut away, as at 45, to substantially fit the corresponding corners on the flask (Fig. 5). Boxes or holders, as 46, are provided on the ends of the base section C of the flask to receive blocks E which form the ends of the molding receptacle. These blocks E in the 20 present embodiment are of metal to chill the end portions of the casting. Projections 47 on the bases of these blocks enter corresponding sockets in the bottom walls of the holders 46 to properly position the 25 blocks therein. The under faces of the blocks D are preferably directly exposed to the atmosphere to facilitate cooling.

Blocks F in the side members B, B of the mold are placed within the flask sections 30 through openings in the outer side walls of these sections and retained therein by key or guard plates 50 which are secured to the sections by screws 51 or other suitable means. The top plates of the members B, B are 35 preferably provided with depending flanges 52 which fit within corresponding indentations in the blocks. Similarly upstanding flanges 53 are provided upon the inner edges of the base plates of these members. In order to 40 support the blocks F at an interval from the base walls of the members, I have provided ribs or projections 54. This provides an air chamber beneath the blocks for the free circulation of air. Ribs or projections 55 on the plates 50 perform a like function. The flanges 53 preferably contact with the plates 41 and 42 in the bottom section C when the side members are moved to closed 45 position in the manner which will be presently described, and thus protect the blocks D and F from impact and possible injury. Boxed sections 56 are provided at the ends of the side members B, B to hold in position chill blocks G, G and H, H, the 50 inner faces of these sections being provided with tapering ribs, as at 57, to hold these chill blocks in proper position longitudinally, also to prevent them from rising when the molten metal is poured into the 55 casting chamber. These ribs exert a wedge action on the chill blocks and thus firmly hold together the blocks at each end of the mold. The blocks G, G are alike except that their form is reversed. Blocks H, H are 60 alike in the same manner.

A pair of upstanding lugs 60 is provided on the base A on each side of the mold and each pair supports a pivot rod 61. A sleeve 62 is mounted on each of these rods between the lugs and this sleeve carries a pair of 65 eccentrically mounted rollers or cams 63. Lugs 64 on the side wall of the members B are disposed above and below each of these rollers or cams. An operating lever 65 is formed on or attached to each sleeve so that 70 when these levers are raised, the side members B will be swung on the pivot rod 33 to closed position. Similarly when the levers are depressed, these side members will 75 be moved to open position.

One of the lower chill blocks E is shown in detail in Figs. 8 to 10 inclusive, Fig. 8 being a side elevation, Fig. 9 a bottom plan view, and Fig. 10 an end elevation. A portion of the molding cavity 66 is included in 80 this block and the portion of the brake shoe casting formed therein is chilled. It will thus be seen that this block chills the end of the shoe and also the end portion of the 85 sides and face.

In addition to acting as chills the blocks G perform the functions of pouring gate and mold for one end lug. One of these blocks is shown in detail in Figs. 11 to 13 inclusive, Fig. 11 being a side elevation, Fig. 95 12 a bottom plan view, and Fig. 13 an end elevation. A channel 67 is formed between these blocks and the molten metal enters the casting chamber therethrough. The end lug is formed in the cavity 68, one-half of the 100 cavity being in each block as in the case of the pouring gate channel.

The upper chill blocks H perform the same functions as the blocks G except that of acting as a pouring gate. One of these 105 blocks is shown in detail in Figs. 14 to 16, Fig. 14 being a side elevation, Fig. 15 a bottom plan view, and Fig. 16 an end elevation. The end lug is formed in the cavity 69 corresponding to the cavity 68 in the 110 block G. The upper chill blocks G each rest on the lower chill block E and the upper surface of the steel brake shoe shell 71 (Fig. 5). The chill blocks H likewise 115 rest on the lower chill block E and the steel brake shoe shell 71. Where no chilling of the casting is required, refractory blocks of like form would be substituted for these chill blocks.

Shoulders 70 are formed on the end chill 120 blocks E to support a steel brake shoe shell, as 71 and maintain this shell in proper vertical position. In the present embodiment, this shell forms the top wall of the molding receptacle and is held in place upon the shoulders 70 by the blocks G and H. This shell preferably has no openings provided in its top wall except a pouring opening 72 and end lug openings 73. When the brake shoe is to be provided with steel end lugs 125 130

attached to the shell, as distinguished from cast lugs, no end lug openings would be provided in the shell. This steel end lug construction may be used in the present mold 5 as the steel lugs will enter the cavities 68 and 69 in the blocks G and H. As steel lugs of this type are well known in the art, no illustration or detail description is necessary. The molten metal enters the perforations, as 74, in the side and end walls of the shell and firmly incorporates the shell in the casting. In the present embodiment, the center lug 75 is formed of ductile metal and attached to the shell by flanges 76 projecting through the shell and bent inwardly beneath the top wall thereof. The pouring opening 72 is preferably larger than the corresponding openings in the blocks to prevent the inflowing molten metal from fusing 15 the shell. On the other hand, the end lug openings 73 are preferably smaller than the openings in the blocks so as to anchor the end lug to the body metal of the shoe. The chill blocks G and H are preferably tapered, 20 as at 77 and 78 respectively, so that when the side members B are opened and closed there is no scraping action. These chill blocks G and H may be made in different 25 vertical thicknesses to permit the manufacture of steel shell brake shoes of varying thickness and without changing any of the other parts of the mold.

In the operation of this mold, it is placed in open position, that is the handles are 30 moved downwardly, thus withdrawing the side members B from contact with the stationary base member C. The end chill blocks E are then placed in their respective holders. The steel shell, as 71, is next 35 placed in the mold with its ends resting on the shoulders 70 provided for the purpose. The chill blocks G are then placed on top of the corresponding block E at one end of the mold and the chill blocks H similarly 40 placed at the opposite end. The side members B are then moved to closed position by the levers 65 and the molten metal poured into the channel in the pouring gate until the mold is filled. After the metal has 45 sufficiently hardened, the members B are moved to open position, leaving the finished casting resting on the refractory blocks of the stationary members C of the mold and with all of the chill blocks in the same 50 position as placed when preparing the mold. The brake shoe with all chill blocks surrounding the ends is now removed from the mold and placed in a proper place to cool. The mold is now made ready for another pouring by inserting another set of 55 chill blocks, the set just used being too hot to properly chill the next casting. When the finished shoe cools the chill blocks drop away from it as with chilled shoes cast in ordinary sand molds. When the chill blocks

have cooled sufficiently they may be again used. A distinct advantage in having the chill blocks and pouring gate combined is that the deterioration from successive pourings through a cast metal pouring gate 70 while still hot is avoided. The metal is only poured through the gate when the chill blocks are cold. By having the end chills G and H separated no difficulty results from shrinkage of the shoe longitudinally which 75 would otherwise tend to produce a binding action and cause trouble in getting the shoe from the mold.

It will be obvious that this mold is exceedingly simple in construction, consisting 80 of but two movable members, the stationary base member and the refractory and chill blocks. No cope, end members, or cores need be used. The design of steel shell brake shoe having perforations along the 85 sides and ends, enables very satisfactory venting through these perforations and the spaces between the refractory blocks. With the section of the steel shell on each side of the center lug exposed to the atmosphere 90 and with the superior venting provided, the shoe will cool much more rapidly than sand-molded shoes.

It will be noted that there is no scraping 95 action whatever in the operation of the mold nor in the removal of the shoe from the mold. It should also be noted that none of the refractories have any depressions in them, all of them presenting only flat or 100 curved surfaces to the cast metal.

A modified form of casting mold embodying certain of the principles of my invention is shown in Figs. 19 to 22 inclusive. This type is particularly adapted for use 105 where no chilling action is required. Instead of mounting block holders on the stationary bottom member of the mold as was described in connection with the previous embodiment, end members M are pivotally mounted on the base A. These end members are moved to open or closed position by levers 101 in the same manner as the side members of the mold. Each of these end members in the present embodiment comprises a chambered flask section 102 in which 110 are mounted refractory blocks 103. These blocks are held in place within the section by a key or guard plate 104 which is secured to the section by screws 105 or other suitable means. The steel shell 71 is placed within 115 the mold in the same manner as was described in connection with the previous embodiment and rests on shoulders 106 formed in the faces of the refractory blocks in the end members. The end members are moved to closed position and the shell placed with 120 its ends resting on the shoulders 70. After the insertion of the shell, combined pouring gate and end lug mold 107 is then placed at 125 one end of the shell and the end lug mold 130

110 at the other end. The side members are then moved to closed position whereupon ribs 109 on holder 108 firmly hold and position this pouring gate. The combined pouring gate and end lug mold 107 in the present embodiment is formed of burnt or hard sand. The end lug mold 110 at the opposite end of the mold proper is also formed of hard or burnt sand and rests upon the steel shell 71. This mold 110 is held in position thereon by triangular ribs 111 (Fig. 22) formed on the side members B. These ribs fit within corresponding depressions in the end lug mold.

15 The end members M of the mold are preferably tapered, as at 112, on their inner faces to prevent any scraping action when the mold is opened. The end faces of the side members B are shaped to conform. At the 20 completion of the molding operation, the end members are first moved to open position and then the side members are likewise moved. The parts 107 and 110 remain on the casting and are knocked off when the 25 latter is lifted from the mold.

18 In Figs. 23 to 25 inclusive is shown a modified form of pouring gate for use with the mold construction shown in Figs. 19 to 22, Fig. 23 being a plan view, Fig. 24 a central vertical section, and Fig. 25 an end view. This construction comprises a metal box 115 adapted to receive a filling 116 of green sand which is molded with a pouring hole 117 and end lug cavity 118. This metal 30 box may be repeatedly used with new fillings. The filled box is placed in the mold proper and held therein in the manner described for the burnt sand gate 107 in the previous embodiment.

40 Fig. 26 shows a section of a box 119 similar to that shown in Fig. 24, except that this box is intended for use with a steel shell construction in which steel end lugs are attached to this shell. No mold cavity for the 45 end lug is therefore necessary in the green sand filling. A similar cavity 120 to admit the steel lug is, however, provided by an extension of the end wall of the box.

50 I am aware that numerous changes in the form and arrangement of parts of my mold may be made by anyone skilled in the art without departing from the spirit of my invention and I reserve the right to make all such as fairly fall within the scope of the 55 following claims.

I claim as my invention:

1. A casting mold comprising a bottom section, relatively movable side sections, and a metal plate adapted to be supported 60 by certain of said sections and to form with said sections a molding receptacle when said sections are in closed position.

2. A casting mold comprising a bottom section, relatively movable side sections, 65 end sections carried by said bottom section,

and a metal shell adapted to be supported by certain of said sections and to form with said sections a molding receptacle when said sections are in closed position.

3. A casting mold comprising a bottom 7 member, relatively movable side members, blocks carried by each of said members, and a metal shell adapted to be supported by certain of said members and to form with said blocks a molding receptacle when said members are in closed position.

4. A casting mold comprising a bottom member, relatively movable side members, 80 end members carried by said bottom members, blocks mounted in each of said members, and a metal shell adapted to be supported by certain of said members when said members are in closed position and to form with said blocks a molding receptacle.

5. In a casting mold, a molding receptacle 85 comprising a plurality of sections arranged to form the bottom, side and end walls thereof, and a metal plate adapted to be supported by said sections and to form the top wall of said receptacle, certain of said 90 sections being formed of a plurality of separate blocks.

6. In a casting mold, a molding receptacle comprising a plurality of separable sections 95 arranged to form a portion of said receptacle, and a metal shell forming the remaining portion of said receptacle, certain of said sections being formed of a plurality of separate blocks.

7. In a casting mold, a molding receptacle comprising a plurality of sections arranged to form a portion of said receptacle, and a metal shell forming the remaining portion of said receptacle, certain of said sections being formed of a plurality of refractory 100 blocks.

8. In a casting mold, a molding receptacle comprising a plurality of relatively movable sections forming a portion of said receptacle, and a separable metal shell forming 110 the remaining portion of said receptacle, each of said sections comprising a plurality of blocks secured together.

9. In a casting mold, a molding receptacle comprising a plurality of sections arranged 115 to form the bottom, side and end walls of said receptacle, and a metal member forming the top of said receptacle and being adapted to be incorporated in the casting when the mold is filled, certain of said 120 sections being formed of a plurality of separate blocks.

10. In a casting mold, a molding receptacle comprising a bottom section, end sections, movable side sections, and a top section adapted to rest upon said end sections and to be held in place thereon by said side sections when said side sections are in closed position.

11. In a casting mold, a molding re-

- ceptacle comprising bottom and side sections, each including a plurality of separate blocks, end sections, and a spaced metal plate forming the top section of said receptacle.
12. In a casting mold, a molding receptacle having an opening in its top, and a separable metal plate forming the closure for said top and being provided with a pouring passage, said plate being adapted to be incorporated in the casting when the mold is filled.
13. In a casting mold, a molding receptacle open at the top, a separable metal plate forming the top of said receptacle and being provided with a pouring passage, said plate being adapted to be incorporated in the casting, and a pouring gate adapted to be secured to said plate with its pouring passage communicating with the passage in said plate.
14. In a casting mold, a molding receptacle open at the top and comprising a plurality of sections, certain of which are movable, a metal plate forming the top of said receptacle and being provided with a pouring passage, and a pouring gate secured upon said plate by certain of the movable sections of said receptacle when said sections are in closed position, the pouring passage in said gate communicating with the passage in said plate.
15. In a casting mold, a molding receptacle open at the top and comprising a plurality of sections, certain of which are movable, a separate metal shell fitting within said receptacle and forming a closure therefor, said shell being provided with a pouring passage, and a pouring gate of refractory material adapted to be clamped upon said shell by the movable sections of said receptacle when said sections are moved to closed position, the pouring passage in said gate being adapted to communicate with a corresponding passage through said shell.
16. In a casting mold, a molding receptacle comprising end sections, side sections cooperating with said end sections, certain of said sections being movable, and a top section adapted to rest on certain of said sections and to be clamped in position thereon by certain other sections by the moving of said other sections to closed position.
17. In a casting mold, a molding receptacle comprising end sections, movable side sections cooperating with said end sections, and a top section and pouring gate section adapted to be clamped in position by said side sections when said side sections are moved to closed position, said pouring gate communicating with the casting chamber in said receptacle through a passage in said top section.
18. In a casting mold, a molding receptacle comprising a bottom section, end sections, movable side sections cooperating with said bottom and end sections, a top section adapted to rest on certain of said sections, and a pouring gate adapted to rest on said top section and communicate with the casting chamber in said receptacle through a passage in said top section, said top section and said pouring gate being clamped in position by said side sections when said side sections are brought to closed position.
19. In a casting mold, a molding receptacle open at the top, a separate metal plate forming a closure for said top and having a pouring passage therein, and a pouring gate mounted on said plate with its pouring passage forming a continuation of the passage in said plate, the passage in said plate being of greater area than the immediately adjacent portion of the passage in said gate to prevent the inflowing molten metal contacting with said plate.
20. A mold for casting brake shoes comprising a base, bottom, end and side mold sections mounted on said base, and a metal back adapted to rest upon certain of said sections and to be held in position thereon by certain other sections to form with said sections a molding receptacle, said back being incorporated into the casting when the mold is filled.
21. A mold for casting brake shoes comprising a plurality of separable mold sections co-operating to form the bottom, side and end walls of the mold, and a metal shell within the mold and held against removal thereby, said shell forming a portion of the top wall of the mold and being constructed to become interlocked with the casting when the mold is filled.
22. A mold for casting brake shoes comprising a plurality of separable mold sections co-operating to form the bottom, side and end walls of the mold, and a ductile metal shell adapted to rest upon said sections and to be held in position thereon by said sections to form the top wall of the mold, said shell being constructed to become interlocked with the casting when the mold is filled.
23. A mold for casting brake shoes comprising a plurality of separable mold sections co-operating to form the bottom, side and end walls of the mold, and a pan-shaped metal shell forming a closure for the top of said mold, said shell being constructed to become interlocked with the casting when the mold is filled.
24. In a casting mold, the combination with a sectional flask of molding receptacle sections carried by the corresponding sections of said flask, frame members on certain of said flask sections co-operating to

- form a pouring gate holder, and blocks supported by said sections and held in position thereon by said frame members when said sections are in closed position, said blocks 5 co-operating to form the pouring gate of the mold.
25. In a casting mold, the combination with a sectional flask of molding receptacle sections carried by the corresponding sections of said flask, frame members on certain of said flask sections co-operating to form a pouring gate holder, and chill blocks supported by said sections and held in position thereon by said frame members when 10 said sections are in closed position, said blocks being clamped in position on said flask by the moving of the flask sections to closed position and co-operating to form the pouring gate of the mold.
- 15 26. In a casting mold, a molding receptacle comprising a plurality of separable sections arranged to form a portion of said receptacle, and a metal shell forming at least a portion of the remainder of said receptacle, certain of said sections being formed of a plurality of separate blocks.
- 20 27. In a casting mold, a molding receptacle comprising a plurality of sections arranged to form a portion of said receptacle, 30 and a metal shell forming at least a portion of the remainder of said receptacle, certain of said sections being formed of a plurality of refractory blocks.
- 25 28. In a casting mold, a molding receptacle having portions thereof formed by readily separable self-supporting blocks, and a metal shell detachably supported by said blocks and forming another portion of the molding receptacle.
- 30 40 29. In a casting mold, a molding receptacle having bottom, end and side walls, a metal shell supported thereby and adapted to form the top wall of the molding receptacle, said metal shell having a pouring opening and a pouring gate cooperating 45 with said opening.
30. As an article of manufacture, a mold constructed at least in part of relatively movable sections adapted to expand or contract while maintaining a molding receptacle of substantially constant overall dimensions, and a metal plate cooperating 50 with said sections and forming another portion of the molding receptacle.
31. As an article of manufacture, a mold 55 constructed at least in part of relatively movable sections adapted to expand or contract while maintaining a molding receptacle of substantially constant overall dimensions, a metal plate cooperating with 60 said sections and forming another portion of the molding receptacle, said plate being adapted to become incorporated in the finished casting.
32. As an article of manufacture, a mold 65 having a molding receptacle formed in part by a plurality of relatively movable sections and in part by a metallic plate co-operating therewith and adapted to become incorporated in the finished casting. 70
33. As an article of manufacture, a mold having a molding receptacle formed in part by a plurality of relatively movable sections and in part by a metallic plate co-operating therewith and adapted to become incorporated in the finished casting, said sections being supported for separation about pre-determined axes. 75
34. As an article of manufacture, a molding receptacle formed in part by a plurality of spaced blocks and in part by a metallic plate co-operating therewith and adapted to become incorporated in a finished casting. 80

CLIFTON D. PETTIS.
